DISPENSER FOR PASTELIKE SUBSTANCE
HAVING A VANCED ROTARY EXTRUDING
ELEMENT

Floyd L. Eddy, Los Angeles, Calif.

Application January 19, 1948, Serial No. 3,046

3 Claims. (Cl. 222—413)

1

This invention relates generally to dispensers for measuring out standard quantities of substances, and is particularly useful for the dispensing of plastic or paste materials such as soap paste.

Soap in the form of paste is superior for some purposes to soap in either the liquid, powder, or the solid form. However, in industrial establishments and the like, the use of soap paste, where it would otherwise be highly desirable, has been prevented by the unavailability of suitable dispensers. It is highly important in such places to provide a dispenser that can be easily manipulated to deliver a measured quantity of soap paste.

An object of the invention is to provide a paste dispenser that is simple to operate and delivers a fairly accurately measured quantity of soap paste in response to a predetermined operation.

Another object of the invention is to provide a paste dispenser which is rugged, durable, and long-lived.

Another object is to provide a paste dispenser that can be manufactured at reasonable cost.

Other more specific objects and features of the invention will become apparent from the following description of a preferred embodiment of the invention with reference to the drawing, in which:

Fig. 1 is a front elevation of a dispenser in accordance with the invention;

Fig. 2 is an end elevation looking at the left end of Fig. 1;

Fig. 3 is a horizontal section taken in the plane III—III of Fig. 1; and

Fig. 4 is a vertical section taken in the plane IV—IV of Fig. 3.

As clearly shown in the drawing, a dispenser in accordance with the invention may comprise a receptacle 10 having a semi-cylindrical bottom wall 11 which merges at its upper edges into flat front and rear walls 12 and 13 respectively, the three wall sections 11, 12, and 13 preferably being formed from a single sheet of metal. The container is completed by end walls 14 and 15, and a pivotally connected lid 16. The pivotal connection between the lid and the rest of the container may be effected by a hinge wire 17 which extends through front and rear flanges on the lid and through the front and rear walls 13 and 12, the ends of the wire being flattened to retain it. To support the container against a wall a bracket 18 may be provided on the rear thereof, this bracket being of general U-shape, with the cross part of the U welded or otherwise

2

secured to the rear flat wall 12 of the container, and the ends of the legs of the U being bent parallel to the rear wall 12 as indicated at 181 in Fig. 1. These flattened portions may have screw holes 182 therein.

The soap is dispensed through an opening 19 in the left end wall 14, and the movement of the soap paste through the opening is effected by rotating a crank 20 which projects from the right end wall 15. Thus the crank 20 extends through a bearing bushing 21 in the end wall 15 and is threaded into an axle 22 which extends between the bushing 21 and a corresponding bushing 23 in the opposite end wall 14. A screw 24 extending through the bushing 23 and screwed into the left end of the axle 22 rotatably supports the left end of the axle.

Mounted at spaced intervals longitudinally along the axle 22 are a plurality of vanes 26. These vanes 26 are of interrupted circular shape and may be stamped from sheet metal, each having an integral flange 26a at the center of size to be pressed on the axle 22. Positive anchoring of the vanes 26 to the axle 22 may be insured by spot welding each collar 26a to the axle at one or more points as indicated at 27.

The leading edges 26b of each vane are bent out of the plane of the collar 26a, whereas each trailing edge 26c is substantially flat and in the plane of the center portion of the vane, as best illustrated in Fig. 3.

In operation, during each half revolution of the crank 20, one half of the end vane traverses the opening 19 and forces a substantially uniform quantity of soap paste out of the opening. At the same time, the remaining vanes advance the main body of the paste along the curved bottom wall 11, to replace the quantity that was dispensed through the aperture 19.

An important feature of the invention is the use of the plurality of interrupted vanes 26, which not only insures positive feed of a fixed quantity of paste through the orifice during each half revolution, but insures the maintenance of a quantity of paste in the end of the container adjacent the discharge aperture 19.

In contrast, a solid or continuous helix has been found by experiment to fill with soap paste, which rotates with it and fails to feed paste to the discharge opening. It is to be understood in this connection that the invention is to be used with paste material of such thick or stiff consistency that it is substantially incapable of flowing.

55 It will be noted from the drawing that all of

the vanes 26 are aligned longitudinally with each other, and that the leading edge 26b of each vane at its outer end is substantially in the same transverse plane as the trailing edge 26c of the next adjacent vane. It has been found by experiment that this arrangement of the vanes is more effective in handling thick soap paste than other arrangements.

Although for the purpose of explaining the invention, a particular embodiment thereof has been shown and described, obvious modifications will occur to a person skilled in the art, and I do not desire to be limited to the exact details shown and described.

I claim:

1. A dispenser of the type described comprising a casing having a cylindrically curved bottom wall, and end walls associated therewith, one of said end walls having a discharge aperture therein; screw means within said container having its axis substantially concentric with said cylindrically curved bottom wall, and means for rotating said screw means; said screw means comprising a central shaft having a plurality of axially spaced vanes thereon, each vane having an inner end adjacent said shaft and an outer end radially displaced from said shaft, and having a trailing edge and a leading edge with the trailing edge nearer said discharge aperture than said leading edge, that portion of the leading edge most remote from said aperture being substantially in the same transverse plane as the trailing edge of the next adjacent vane, and the entire trailing edge of each vane lying substantially in a plane normal to said axis, and the leading edges diverging progressively from said plane from their inner ends to their outer ends.

2. A dispenser of the type described comprising: a casing having a semi-cylindrical bottom wall and vertical side walls rising from the upper edges of said bottom wall, and end walls closing said side and bottom walls, one of said end walls having a discharge aperture adjacent its lower end; screw means within said container having its axis substantially concentric with said cylindrically curved bottom wall, and means for

rotating said screw means; said screw means comprising discontinuous vanes each having an arcuate outer edge approximately concentric with respect to said bottom wall and of slightly less radius than said bottom wall and being continuous from said outer edge to said axis, at least the end vane adjacent said aperture having a trailing edge lying substantially entirely in a transverse plane closely adjacent said apertured end wall, and each of said vanes having a leading edge more remote from said apertured end wall than its trailing edge.

3. A dispenser of the type described comprising: a casing having a semi-cylindrical bottom wall and end walls closing said bottom wall, one of said end walls having a discharge aperture adjacent its lower end; screw means within said container having its axis substantially concentric with said bottom wall, and means for rotating said screw means; said screw means comprising a central shaft having a plurality of axially spaced vanes thereon, each vane having a trailing edge and a leading edge with the trailing edge nearer said apertured end wall than is the leading edge, that portion of the leading edge of each vane most remote axially from the trailing edge being substantially in the same transverse plane as the trailing edge of the next adjacent vane, and said trailing edges of said vanes lying in planes normal to said axis.
